[57] CLAIM

The ornamental design for the camera bracket, as shown and described.

DESCRIPTION

FIG. 1 is a perspective view of a camera bracket showing my new design;

FIG. 2 is a top plan view thereof shown on a larger scale;

FIG. 3 is a side elevational view thereof;

FIG. 4 is an opposite side elevational view thereof;

FIG. 5 is a front elevational view thereof;

FIG. 6 is a rear elevational view thereof; and

FIG. 7 is a bottom plan view thereof.

The broken line disclosure of a pair of cameras mounted on the camera bracket in FIG. 1 is for illustrative purposes only and forms no part of the claimed design.
